UNITED STATES PATENT OFFICE

ARTHUR TERREY, OF LONDON, ENGLAND

ROTARY PRINTING PRESS

Application filed April 13, 1929, Serial No. 354,951, and in Great Britain April 19, 1928. Renewed December 31, 1931.

This invention relates to rotary perfecting presses of the type having a single deck, comprising two type cylinders each coacting with two or more impression cylinders, and particularly to such presses of the unit or low construction type.

I am aware it has been proposed to construct a press of the above mentioned type in which one perfected web has been deflected out of its path to permit the crossing over of a web printed on one side only in its passage to receive its second impression.

The object of this invention is to provide an improved construction of press.

To this end, in a rotary perfecting press of the abovementioned type, the two webs are perfected simultaneously, the webs being caused to pass or cross one another when printed with one impression only while travelling from one impression cylinder to the other for receiving impressions on both sides thereof.

The webs of paper may enter either at the top or bottom of the press.

The invention will now be described with reference to the accompanying diagrammatic drawings, in which Figure 1 is a front elevation of one form of perfecting press constructed in accordance with this invention; Figures 2 and 3 are plan and side elevation respectively, and Figure 4 is a perspective view of a detail.

a and *b* are two webs of paper run in at the bottom of the deck.

The web *a* is passed from the reel (not shown) to the first impression cylinder *d* where it receives its print from the usual type cylinder *c*. After leaving the cylinder *d* the web passes above the deck to the first turner bar *e*, where it obtains a right angled turn, to the roller *f*. Returning from said roller, the web takes another right angled turn, by passing over the second turner bar *e*¹, and thus regains its original position. On leaving the said turner bar *e*¹, the web then passes over the rollers *g* and *h* to the second impression cylinder *d*¹ where it is perfected, and from there it is taken to the usual folder.

Similarly with the running of the web *a*, the web *b* passes from its reel to its first im-

pression roller *d*² and thence takes a path above the deck and through the loop formed by the web *a*, by virtue of the turner bars *e*¹, (see Figure 4) to the second impression cylinder *d*¹, where it receives its second impression, and so on to its separate folder.

It will be seen that by diverting the web *a*, a loop or clearance is effected through which the web *b* can pass freely for its second printing, and further the crossing of the webs takes place within the press.

It is obvious that it is essential for one web to pass the other owing to the direction of rotation of the cylinders and also to the fact that each web must carry an inner and outer impression.

With a rotary printing press constructed in accordance with this invention, it will be observed that two machines have been combined into one thus doubling the printing capacity and output of each deck, and, with the addition of other folders to the machine, two sets of the same product are delivered.

Furthermore, the running speed being normal, the output is increased twofold at a safe speed and without affecting the quality of the print.

What I claim is:—

1. A perforating press of the character described comprising a pair of printing cylinders, means for feeding a web to each printing cylinder in a separate path, and turner bars and rollers for guiding the webs to pass and cross over each other, whereby each web may be led from one printing cylinder to the other for simultaneously receiving an impression upon both sides thereof.

2. A perfecting press of the character described comprising a pair of diametrically opposed printing cylinders, means for feeding a web to each printing cylinder in a separate path, and means for guiding one of the webs to pass and cross over the other, whereby each web may be led from one printing cylinder to that diametrically opposed for simultaneously receiving an impression on both sides thereof.

In testimony whereof he affixes his signature.

ARTHUR TERREY. 100
